UNITED STATES PATENT OFFICE.

EDGAR H. CROSSEN, OF FRANKLIN, PENNSYLVANIA.

OIL-ENGINE.

1,148,577.

Specification of Letters Patent. Patented Aug. 3, 1915.

Application filed April 12, 1913. Serial No. 760,761.

To all whom it may concern:

Be it known that I, EDGAR H. CROSSEN, citizen of the United States, residing at Franklin, in the county of Venango and State of Pennsylvania, have invented certain new and useful Improvements in Oil-Engines, of which the following is a specification.

The object, construction and operation of my improved oil engine are herein set forth with sufficient clearness to enable those skilled in the art to which it appertains, to make and use the same.

The object of this invention is, to provide an internal-combustion motor that is adapted to utilize the heavier hydro-carbon oils, such as crude petroleum and its heavier, refined and semi-refined products, for fuel purposes.

The construction by which the above object is attained, is clearly shown in the drawings which form a part hereof, the respective figures of which are as follows:

Figure 1 is a central, longitudinal section of a cylinder of an internal-combustion motor, embodying my invention and showing the piston at the forward end of its stroke. Fig. 2 is the same view, but showing the piston at the rear or compression-end of its stroke. Fig. 3 is an end view of the piston, showing the combustion-chamber end thereof and the vaporizing-plate. Fig. 4 is a side elevation of a governing mechanism which may be used with my improved motor. Fig. 5 is a detail of said mechanism.

The same reference characters are applied to identical parts in all the views.

My invention, which is clearly defined in the claims, is equally applicable to either a two-stroke cycle or a four-stroke cycle engine, but, as illustrated in the drawings, my invention is applied to a two-cycle engine of the three-port type, in which the front end of the cylinder is closed and performs the functions of an air-pump, into which the charge of air is drawn and from thence transferred to the combustion-chamber of the cylinder.

The novel features which constitute my invention, consist of a vaporizing-chamber, composed of an interior lining of the breech of the cylinder, or a false head which is insulated from the water-cooled wall of the cylinder by a non-heat-conducting material,

so that it will become highly heated, in combination with a vaporizing-plate attached to the rear end of the piston and also arranged to become heated to a high degree of temperature by the heat of combustion, and so positioned that it is not materially affected by the cooling action of the jacket-water. There are also other novel features of construction and operation which will appear in the following description.

Referring to Figs. 1 and 2 of the drawings, the construction here shown is substantially as follows:—A motor-cylinder is formed at the rear end into a combustion-chamber 1, in which a piston 2 operates, and, as here shown, said cylinder is formed at its forward end into a pump-chamber 3, into which the air for combustion and power-development, is drawn through the port 4, when said piston is in the position shown in Fig. 2. As said piston travels to the forward end of its stroke, as shown in Fig. 1, and uncovers the by-pass port 5, the air which is now compressed in the pump-chamber passes back into the combustion-chamber through said port 5. Into the by-pass passage 6 is inserted a pipe 7, through which water is introduced into the combustion-chamber by the inductive action of the air, as it passes into said chamber 1.

The breech or rear end of the cylinder is provided with a head 8 of substantially the usual construction, but I insert within the same a novel element, consisting of a vaporizing-head 9 or lining, composed of comparatively thin metal, which fits within the main head 8 and conforms closely to the inner conformation thereof. Between the juxtaposed faces of heads 8 and 9 is interposed a suitable insulating material or non-heat-conducting substance 10, which is preferably asbestos in some suitable form that will prevent any cooling effect upon said head 9 by the water in the jacket 11, and this causes said head 9 to become highly heated by the heat of combustion in the combustion chamber. To the rear end of the piston 2 is affixed a vaporizing plate 12 which is preferably dished somewhat and positioned with its concave face toward said head 9. Said plate 12 is attached to the piston 2 in such a manner that there is preferably a certain amount of intervening space between the two, so that nearly the entire surface of said plate is exposed to the action of the heat in

the combustion chamber and because of this, it becomes highly heated. The method of attaching said plate to said piston is such as to minimize the conduction of heat from the plate by the piston, but the exact manner of said attachment is not material, otherwise considered.

When the piston is in the position shown in Fig. 2, a nearly surrounded or inclosed vaporizing chamber is formed, the walls of which are formed by the head 9 and the vaporizing plate 12, and in this way a highly heated vaporizing chamber is formed.

A suitable fuel-oil injector 13 is inserted through heads 8 and 9 and so positioned that the oil entering the vaporizing chamber therethrough strikes upon plate 12, and because of said heated condition of said plate, said oil is resolved instantly into vapor at the instant just previous to ignition.

The water which enters the combustion chamber through pipe 7, is caused to flow by the inductive action of the current of air, as it passes rapidly past the backwardly turned end of said pipe, and, by the time compression in the combustion chamber is complete, this water is converted into steam, which serves several useful purposes, such as preventing the deposit of carbon upon the walls of the cylinder and piston, also preventing the hardening or baking of any carbon which may possibly be deposited in the piston-ring-grooves, thus insuring the proper action and resiliency of the piston rings, promoting complete combustion of the heavier oils, softening somewhat the severity of explosion, and preventing premature ignition, though, as to this latter point, there is not so much liability with my construction, for the reason that the oil is not injected into the cylinder until just previous to the proper instant for ignition, said oil-injection being caused by any suitably-constructed and operated pump, such for instance, as that shown in Fig. 4. In this construction, the pump 14 is in any way suitably mounted upon the bed of the engine, and is supplied with an inlet-pipe 15 and an outlet-pipe 16, which connects to pipe 16 in Figs. 1 and 1. The plunger 14^p of the pump passes through a guide 17 that supports a spiral spring 18, the upper end of which spring bears against a shoulder or washer 19 that is attached to the upper end of said plunger and serves to yieldably retain said plunger at the upper end of its stroke. Said plunger is operated by a lever 20 that is pivoted to the frame or cylinder of the engine by a bolt or pin 21; upon said pin 21 a rocker-arm 22 is also mounted, and to the upper end of said arm is attached one end of a carrier-rod 23, the other end of which is attached to an eccentric—not shown—upon the crank-shaft 65 of the engine, which causes said arm 22 to

vibrate regularly. Upon said arm is formed a contact-boss 24, which, at each vibration of said arm, comes into contact with the lug 25 upon pump-lever 20 and moves the same and plunger 14^p downward against the action of spring 18, and at each downward movement of said plunger, oil is injected through pipe 16 into the combustion-chamber of the cylinder.

The length of stroke of the pump-plunger is normally regulated by means of a screw 26, which limits the upward movement of the lever 20. A governor of the centrifugal type is also provided, which governs the length of stroke of said plunger and the amount of oil pumped, in accordance with the speed and power requirements of the engine, which governing action is accomplished by means of a longitudinally-movable wedge 27 that is actuated by an arm 28 operatively-connected to the stem—not shown—of the governor. Said wedge is carried by a block 29 that is affixed to the base of the governor; the pump-lever 20 is provided with a boss 30, the upper slanting face of which bears against the lower face of said wedge, and as said wedge is automatically moved longitudinally, the pump-actuating movement of said lever 20 is caused to vary, and said variation affects or modifies the amount of fuel-oil injected into the cylinder by said pump.

From the governor-pulley 31, a belt 32 passes around a pulley upon the crank-shaft of the engine. A lever 33, which engages the stem of the governor, passes through the fulcrum 34, and upon the outer end of said lever 33 a weight 35 is mounted, which serves to hold the governing-mechanism in the normal position. I also provide a governor-actuated needle-valve—Fig. 5—for regulating the supply of water furnished to the combustion-chamber through pipe 7. Said valve consists of a body 36, into which leads the supply-pipe 37, that is preferably connected with the water-jacket in the cylinder, and from which leads the outlet-pipe 7^r, to the induction-pipe 7. The fluid-passage in said body 36 is restricted at 38, and in this restricted portion a needle-point 39 is positioned. The stem 40 of said point passes upwardly through the top of the body 36 and to the upper end of said stem is attached a lever 41. A fulcrum 42 for said lever is formed integrally with body 36, and the lever 41 is secured in said fulcrum. In the outer end of said lever 41 is formed a slot 43 for the reception of a vertically and horizontally-adjustable pin 44, which is carried by the governor-lever 33. Through the medium of said pin 44, the needle-valve lever 41 and the thereto-attached needle are actuated in such a manner that the amount of water passing through the needle-valve to the pipe 7 is

automatically regulated to the required amount, as the load upon the engine fluctuates.

I reiterate the statement, however, that 5 any suitable governing devices for the fuel and water entering the combustion-chamber are within the scope of my invention, but inasmuch as mechanism of this character is quite essential for the purpose of economically 10 developing and regulating power in engines of this type, I have here illustrated one suitable form of governing-mechanism, for the purpose of disclosing a practicable, operative invention.

15 It will readily be understood that any suitable insulating material 10 is within the scope of my invention, also that the form and construction of the vaporizing plate 12 could be modified in many ways, as, for instance, 20 being made an integral portion of the piston, and still remain an equivalent for the construction illustrated in the drawings.

The function of the exhaust port E will 25 readily be understood by those skilled in the art of gas engine construction; it will also be understood that the various elements such as the engine bed, the ignition-system, connecting-rod, crank-shaft, fly- 30 wheel, belt-pulleys, etc., (not shown) by means of which, the energy generated in the cylinder is transformed into available power, may be of any well-known or suitable construction.

35 While I have found that the insulating material 10 may be omitted and a dead-air space substituted therefor, the results are not as satisfactory and economical as where the insulation is employed.

40 I claim:

1. In an oil engine, a cylinder, a head for said cylinder having a chamber forming a continuation of the bore of said cylinder, a metallic lining for said chamber, heat-insulating material interposed between the 45 adjacent faces of said lining and the wall

of said head, a piston operating in said cylinder, a concavo-convex plate attached to the rearward end of said piston with its concave face toward said chamber, there 50 being an intervening space between the adjacent faces of said piston and said plate, said plate and said lining being arranged to conjointly form, when the piston is at the rearward end of its stroke, the inclosing 55 walls of a vaporizing chamber having a higher temperature than other portions of the combustion chamber, and means injecting fuel into said vaporizing chamber, when so formed.

2. In an oil engine of the two-cycle type, a motor cylinder inclosed at both ends, one end of the bore of said cylinder forming a combustion chamber, the other end of the bore of said cylinder being adapted to form 65 an air-pump chamber, a metallic lining in the rearward portion of said combustion chamber, a heat-insulating substance interposed between the adjacent faces of said lining and the cylinder wall, an air-by-pass 70 leading from said pump-chamber to said combustion chamber, a water-supply pipe leading into said by-pass, a piston operative in said cylinder between said pump-chamber and said combustion-chamber, a 75 concavo-convex plate attached to said piston and spaced at a distance therefrom, so as to occupy a position within said combustion chamber with its concave face toward said lining, and adapted to form, 80 in conjunction with said lining, when said piston is at the compression end of its stroke, a substantially inclosed vaporizing chamber, and means injecting fuel-oil into said chamber when so formed.

85 In testimony whereof I affix my signature in presence of two witnesses.

EDGAR H. CROSSEN.
